PACKAGE AND ASH TRAY

Maurice T. Groen, New York, N. Y.

Application April 3, 1947, Serial No. 138,122

Term of patent 14 years

(Cl. D80—5)

To all whom it may concern:

Be it known that I, Maurice T. Groen, a citizen of the United States and a resident of New York, in the county of New York and State of New York, have invented a new, original, and ornamental Design for Combination Display Package and Ash Tray, of which the following is a specification, reference being had to the accompanying drawing, forming a part thereof.

Figure 1 is an isometric view of a combination display package and ash tray, showing my new design.

Figure 2 is a top plan view thereof.

Figure 3 is a side elevational view, and

Figure 4 is an end elevational view thereof.

I claim:

The ornamental design for a combination display package and ash tray, as shown.

MAURICE T. GROEN.
